UNITED STATES PATENT OFFICE.

HERMAN L. BERGER AND FRANCIS C. KNOCHEL, OF NEW YORK, N. Y.

SOUND-BOX.

1,248,062.

Specification of Letters Patent.

Patented Nov. 27, 1917.

Application filed August 13, 1917. Serial No. 185,874.

To all whom it may concern:

Be it known that we, HERMAN L. BERGER and FRANCIS C. KNOCHEL, citizens of the United States, and residents of the city of New York, borough of Manhattan, in the county and State of New York, have invented a new and Improved Sound-Box, of which the following is a full, clear, and exact description.

- 10 This invention relates to sound boxes for talking machines, and has for an object the provision of an improved construction whereby the vibration of the sound box will not be transmitted to the stylus.
- 15 Another object in view is to provide a separate support for a stylus formed independent of the parts forming the sound box proper, in order that none of the vibration or movement of the stylus caused by the 20 grooves in a record shall be transmitted to the diaphragm.

In the accompanying drawing:

Figure 1 is a rear view of a sound box disclosing an embodiment of the invention.

- 25 Fig. 2 is an edge view of the sound box shown in Fig. 1.

Referring to the accompanying drawing by numerals, 1 indicates a sound box of any desired kind having a tubular extension 2 30 for being placed in position in the usual goose neck of a talking machine. The diaphragm of the sound box 1 has an arm 3 connected therewith, said arm being pivotally supported by a journal member 4, rotatably mounted in the extension 7 of the plate 8. The arm 3 at its lower end carries a stylus 5 held in position by any suitable means, as for instance thumb screw 6. The plate 8 is provided with an opening at the 40 upper end sufficiently large to slidably fit on the extension 2 to which it may be clamped by a set screw 9. A second opening 10 may be provided for the purpose of reducing the weight although this is not 45 absolutely necessary. The plate 8 is com-

paratively thick and rigid so that when it is clamped to the tubular member 2 a rigid support is provided for the stylus 5 and the arm 3. The plate 8 is adjustably mounted in a sleeve so as to be moved toward and from 50 the sound box. This movement will naturally shift the position of the stylus arm 3 and the needle 5. This adjustability is provided in order that the vibration set up in the plate 8 and that set up in the stylus 3 may be in 55 a certain sense synchronized for clarifying the sound produced by the diaphragm.

What we claim is:

1. In a device of the character described, a sound box, a supporting sleeve extending 60 therefrom, a stylus arm connected to the diaphragm of the sound box, a plate slidably mounted on said sleeve, means for clamping said plate at any desired point on said sleeve, said sleeve being formed with an 65 extension at the lower end, and means for pivotally mounting said stylus arm on said extension.

2. In a device of the character described, a sound box provided with a sleeve, a stylus 70 arm connected with the diaphragm of the sound box, a plate adjustably mounted on said sleeve so as to be moved toward and from said sound box, said plate being formed with an extension at one end, and means for 75 engaging said extension and said stylus arm for pivotally mounting the stylus arm on said extension.

3. In a device of the character described, a sound box provided with a sleeve, a dia- 80 phragm, a stylus arm connected to said dia- phragm at one end, a supporting plate ad- justably mounted on said sleeve, means for pivotally connecting one end of said stylus arm to said plate, and means for locking said 85 plate at any desired point along said sleeve for causing a balancing or synchronizing of the vibrations of the sleeve and stylus arm.

HERMAN L. BERGER.
FRANCIS C. KNOCHEL.
